UNITED STATES PATENT OFFICE

LEO A. MELTZER, OF SEATTLE, WASHINGTON

DESIGN FOR A COMBINED TELEPHONE PAD AND PENCIL HOLDER

Application filed August 6, 1930. Serial No. 36,567. Term of patent 14 years.

To all whom it may concern:

Be it known that I, LEO A. MELTZER, a citizen of the United States, residing at Seattle, in the county of King and State of Washington, have invented a certain new, original, and ornamental Design for a Combined Telephone Pad and Pencil Holder, of which the following is a specification, reference being had to the accompanying drawings, forming part thereof.

I claim—

The ornamental design for a combined telephone pad and pencil holder, as shown.

LEO A. MELTZER.
